UNITED STATES PATENT OFFICE.

HENRY L. GUENTHER, OF LOS ANGELES, CALIFORNIA.

CAN-CAPPING MACHINE.

Application filed December 24, 1919. Serial No. 347,087.

To all whom it may concern:

Be it known that I, HENRY L. GUENTHER, a citizen of the United States, residing at Los Angeles, in the county of Los Angeles and State of California, have invented new and useful Improvements in Can-Capping Machines, of which the following is a specification.

This invention relates to a can capping machine, and particularly pertains to a crimper therefor.

When double seaming machines are used to place the caps upon filled cans, it is desirable to provide means for securely pressing the cap onto the can and crimping the cap in place prior to the first operation of the double seaming mechanism, thus providing a packing action and at the same time temporarily holding the can top in place so that when received by the first spindles of a double seaming machine it will be in proper position upon the can to be accurately seamed.

It is the principal object of the present invention to provide a simple mechanism which may be automatically lowered over the top of a can and which will serve to hold a can lid in position thereover and to crimp the same prior to its delivery to the seaming rolls.

The present invention contemplates the use of a vertically moving spindle, at the lower end of which a packing disk is provided to force downwardly upon a can, and which structure carries a plurality of radially swinging clamping arms adapted to be moved inwardly to crimp the flange of a can top in relation to the can body, after which they may be released and the can with its top temporarily held in position delivered to a seaming mechanism.

The invention is illustrated by way of example in the accompanying drawings, in which—

Fig. 1 is a view in plan, illustrating a can feeding mechanism, in combination with means for placing a cap upon a can, and further showing a carriage by which the cans are transferred from crimping means to seaming rollers (not shown in the drawings).

Fig. 2 is an enlarged view in plan, showing the arrangement of the crimping mechanism and its plurality of arms.

Fig. 3 is an enlarged view in vertical section through the crimping mechanism, as seen on the line 3—3 of Fig. 2, indicating by solid and dotted lines the two positions of the crimping arms.

In the drawings, 10 indicates a movable turret formed with a plurality of radial recesses 11, into which cans may be placed and by which the cans may be transferred to be acted upon by crimping and double seaming mechanisms. The drawings in the present instance do not show any of the double seaming means; it being understood that they may be of the two-spindle type, between which a can may rotate. At one station in the movement of the turret 10 a vertical shaft 12 is mounted. This shaft is adapted to be vertically reciprocated by any suitable mechanism and in synchronism with a can feeding mechanism 13.

As shown, the can feed comprises a horizontal feed disk 14 operating on a vertical shaft, and upon which cans are delivered to be drawn into a runway 15, which is formed between side rails 16 and 17. The runway 15 conforms to the circumference of the disk 14 for a portion of its length and then extends with its center line substantially tangent thereto. Its opposite end terminates near a reciprocating feed and top mechanism 18, to which the cans are delivered from the disk by means of a conveyor chain 19, having upstanding lugs 20 which are adapted to pass in the rear of the cans and to carry them forwardly along the runway.

A star-wheel 21 is interposed at a point in the length of the runway and extends partially across the throat thereof near the disk 15. This star-wheel prevents the cans from becoming jammed in the runway and insures that they will be properly fed to the chain 20. When the cans reach the reciprocating feed mechanism 18 a top 22 is placed upon the can and thereafter a feed plate 23 is reciprocated at right angles to the path of travel of the cans along the runway. This movement is produced by a lever arm 24 which is operated by suitable timing mechanism (not shown in the drawings).

The can and its top are carried forwardly toward the vertical axis of the turret 10 and into a recess 11 in the turret at the station

over which the shaft 12 is supported. When in this position the can 25 and its lid 22 will be as shown in Fig. 3, at which time downward movement of the shaft 12 will be produced by a mechanism operating in synchronism with the slide plate 23. This downward movement will produce two results; first it will carry down a collar 26, secured to the shaft by a pin 27. Mounted below this 10 collar is a helical spring 28 which rests against a pressure disk 29. The disk 29 is splined to the shaft 12 by means of a key 30. This disk has a lower face agreeing in contour with that of the cap and thus will act 15 to exert a downward yieldable pressure upon the cap to pack the contents of the can and to insure that the lid firmly seats over the mouth of the can.

The collar 26 is also provided with a plurality of radially extending ears 31, between which links 32 are pivoted upon pins 33. These links are secured at their lower ends by pins 34 to crimping arms 35. The crimping arms are pivoted midway their lengths 25 upon pins 36 carried by ears formed upon the pressure disk 29. The lower ends of the crimping arms 35 have crimping recesses 37 adapted to receive the marginal flange of the can lid and an inturned finger portion 38 which is intended to produce a crimping action and force the lower edge of the flange around the out-turned flare 39 of the can 25.

In the operation of the crimping mechanism, it will be understood, as before explained, that the shaft 12 will move downwardly and indirectly exert pressure upon the plate 29 through the spring 28. After the plate 29 has become seated upon the top of the can lid and is no more movable, the 40 fulcrum pins 36 will become relatively fixed and will form pivot points around which the arms 35 may swing. Further downward movement of the shaft and its collar will draw the pins 33 downwardly while forcing the links 32 outwardly. As these links are pivoted to the upper end of the crimping arms 35, the lower ends of these arms will swing inwardly and their recesses 37 will register with the circumference of 50 the can top. Force then exerted will crimp the top into position.

As shown in Fig. 2, four crimping arms are provided and it will be seen that by crimping the can top over the flare of the 55 can at three or more points, the top may be held while the can is transferred by the turret to the first station in the seaming operation. It will thus be seen that the crimping mechanism here disclosed will act 60 to provide a combined packing and crimping action and will prepare the cans and their tops for the operation of the double seaming rolls, and it will further be noted that in the event the cap sticks to the plate 65 29 stripper pins 40 will be forced down-

wardly by springs 41 as limited by pins 42 to disengage the cap.

Having thus described my invention, what I claim and desire to secure by Letters Patent is—

1. A can crimping mechanism comprising a vertically moving shaft, a pressure disk slidable vertically on the shaft, a collar carried by the shaft and located above the pressure disk, an expansion spring interposed between the collar and the pressure disk, a plurality of relatively long radially swinging approximately vertical arms pivoted around the pressure disk and having lower crimping portions having crimping recesses 75 at their inner edges with upper and lower walls, and relatively short inclined links forming connections between the upper portions of the arms and the collar, whereby downward movement of the collar, with relation to the pressure disk, will cause outward movement of the upper portions of the arms and an inward crimping action of the lower ends of the said arms.

2. A can crimping mechanism comprising 90 a vertically moving shaft, a pressure disk splined upon said shaft and adapted to move therewith, a collar carried by the shaft, an expansion spring interposed between the collar and the pressure disk, a plurality 95 of radially swinging arms pivoted around the pressure disk, and link connections between the collar and the upper ends of said arms, whereby downward movement of the collar in relation to the fixed position of the pressure disk will cause outward movement of the upper ends of said arms, and an inward crimping action by the lower ends of said arms.

3. A can crimping mechanism comprising 105 a vertically moving shaft, a yieldable pressure disk splined thereupon and adapted to be brought to rest upon the cap of a can, a plurality of radial crimping arms pivoted to the pressure disk and distributed there-around, said arms standing to swing vertically and having recessed lower ends adapted to receive the flange of a can top and to crimp the same, a collar upon the shaft, an expansion spring interposed between the 110 disk and the collar, and link means between the collar and the upper ends of the arms for producing a crimping action upon downward movement of the shaft.

4. A can crimping mechanism comprising 120 a vertically moving shaft, a pressure disk mounted on the shaft at the lower end thereof, a collar mounted on the shaft above the friction disk, an expansion spring interposed between the collar and the pressure 125 disk, a plurality of relatively long upright radially swinging arms pivoted intermediate of their ends around the pressure disk, and provided with lower crimping ends having crimping recesses at their inner edges, and 130

relatively short inclined link connections between the collar and the upper ends of the arms, whereby downward movement of the collar, with relation to the pressure disk, will cause outward movement of the upper ends of said arms and an inward crimping action of the lower ends of the arms.

In testimony whereof I have hereunto set my hand in the presence of two subscribing witnesses.

HENRY L. GUENTHER.
